UNITED STATES PATENT OFFICE.

GEORGE STANDFEST, OF ROCHESTER, NEW YORK,

RAILROAD-SPIKE.

1,103,444.

Specification of Letters Patent. Patented July 14, 1914.

Application filed May 12, 1913. Serial No. 767,148.

To all whom it may concern:

Be it known that I, GEORGE STANDFEST, a citizen of the United States, and resident of Rochester, in the county of Monroe and State of New York, have invented certain new and useful Improvements in Railroad-Spikes, of which the following is a specification.

This invention relates to railroad-spikes, or similar devices, of the type in which teeth or lugs are provided upon the shank of the spike to increase its hold upon a tie or timber in which it is driven, more particularly where these teeth or lugs are so formed that the spike, after being driven into the wood by hammering in the usual manner, may be subjected to a partial rotation whereby the teeth or lugs are forced into solid portions of the wood to lock the spike in place.

In spikes of the type in question it has heretofore been proposed to employ, on one side or on opposite sides of the shank, a series of teeth or lugs extending for nearly its entire length, and to provide the lower end of the spike with a beveled or chisel-shaped point intended to facilitate the driving of the spike. The use of numerous teeth or lugs for the purpose in question, as in such previous constructions, is objectionable, however, as it causes the wood into which the spike is driven to be so broken that the holding power of the spike is seriously impaired. Furthermore, the teeth, extending as they do throughout nearly the entire length of the spike, preclude the close and firm engagement between the upper part of the shank and the wood which is desirable, particularly in a railroad spike, to enable the spike to resist the lateral pressure to which it is subjected by the base of the rail.

One object of the present invention is to produce a spike, of the type in question, in which the teeth or lugs are so formed that the spike may be readily driven into the wood with a minimum destruction of the grain or fiber of the wood, while a powerful hold is attained against longitudinal movement in the direction of withdrawal.

Another object of the invention is to provide for a long and firm engagement between the wood and the upper part of the shank of the spike. To these ends I have found that it is essential to employ a limited number of lateral lugs, two such lugs, in fact, being sufficient, these lugs having

abrupt upper surfaces but being connected with the sharp lower end of the spike by long, smooth, inclined surfaces which are adapted to part the fibers of the wood without substantial injury. To the same end I 60 arrange the lugs in staggered or offset relation, that is, with their abrupt upper surfaces at different distances from the end of the spike; and in order that the spike may be driven straight into the wood the upper 65 lug is preferably made with its upper surface somewhat wider than that of the lower lug, so that the inclined lower surfaces connecting the lugs with the sharp end of the spike are more nearly at equal angles with 70 the length of the spike. To secure the second advantage above pointed out, the lugs are located at a considerable distance from the head of the spike, the upper part of the shank, preferably at least half of its length, 75 being smooth and somewhat tapered from the head downwardly. This form of the spike permits the fibers of the wood to spring back against the shank after the passage of the lugs, so as to give a long, firm 80 bearing of the shank against the wood.

Another object of the invention is to so form the head of the spike that the spike may be turned, when desired, by means of the claw or spike-puller constituting a part 85 of the usual equipment of a railroad construction gang, thus avoiding the necessity of a wrench or special tool for this purpose, and to this end I provide the head of 90 the spike with an upward projection which is sufficiently elongated and narrow to be embraced by such a claw, and which has a widened or overhanging upper extremity adapted to maintain a secure engagement 95 between the spike and the claw, while the claw is being employed to turn the spike, and at the same time affording a wide and firm surface to receive the blows of a sledge in driving the spike.

In the accompanying drawings: Figures 1 100 and 2 are, respectively, a front-elevation and a side-elevation of a railroad-spike embodying the present invention, Fig. 2 showing the spike in engagement with a portion of the base of a railroad rail; Fig. 3 is a top-view of the spike; and Fig. 4 is a horizontal section on the line 4—4 in Fig. 1.

The illustrated embodiment of the invention has a shank 6 of which the upper part 105 is smooth and round and is slightly tapered 110

downwardly, the shank terminating, at its lower end, in a sharp and somewhat wedge-shaped point 7.

The holding-lugs which constitute a feature of the present invention are located at the lower part of the shank 6, occupying, in fact, somewhat less than one-half of the length of the shank. These lugs have abrupt upper surfaces 8 and 9, respectively, but they are connected with the point 7 by long, smooth, tapered surfaces 10 and 11, as shown in Fig. 1. The surface 8 is somewhat wider than the surface 9, so that the surfaces 10 and 11 are arranged at nearly equal angles to the axis of the spike.

The head of the spike is provided with a flange 12, which projects wholly at one side of the spike, and the head has a forward projection or nose 13, which is adapted to overhang the base of a railroad-rail in the usual manner, and as shown in Fig. 2. The head comprises also an upward projection which is narrow and elongated, as shown in Fig. 3, and which has a comparatively narrow lower portion 14, and a wider upper extremity 15.

The spike above described may be used in two ways. It may be started in a railroad-tie in the position shown in Fig. 2, and simply driven into the wood until the head engages the base of the rail. In this case the grain of the wood, owing to the peculiar form of the shank and of the holding-lugs, will spring back against the shank and above the surfaces 8 and 9 sufficiently to afford a firm hold for the spike so that it is not essential that the spike be turned after having been driven home. In case it be desired, however, to turn the spike in the manner characteristic of spikes of the type in question, the spike is started into the wood in a position at an angle of 90° to the final position of the spike. In this case the flange 12 at first overhangs the base of the rail, and comes into engagement with the base when the spike has been fully driven home, thus determining the depth to which the spike is driven. A claw may then be engaged with the head of the spike, the prongs of the claw engaging the sides of the narrow portion 14 of the head, and the spike may then be given a quarter-turn,

thus bringing the nose 13 of the spike into engagement with the rail, as in Fig. 2. By this partial rotation the holding-lugs are turned into unbroken wood, thus firmly seating them in the wood and making it difficult to withdraw the spike by a direct pull.

When the spike is used in the manner last described it may be turned back to its original position for the purpose of withdrawing it. Owing to the provision of a flange at one side only of the spike, it is also possible to disengage the spike from the rail and permit the rail to be removed and replaced without withdrawing the spike from the tie. For this purpose the spike is given a further quarter-turn thus turning the surface 16 of the head toward the rail, and as this surface is substantially in alinement with the side of the shank and with the edge of the rail, the rail may then be lifted without impediment. After the rail has been replaced the spike may be turned back again to fix the rail in place by engagement with the nose 13 of the spike.

I claim:—

1. A spike comprising a head having a non-circular part by which it may be turned; a round shank which is substantially smooth in its upper part, and for at least one-half of its length, and sharp at its lower end; and two lugs with abrupt upper surfaces, the lugs being rounded in horizontal section, projecting on opposite sides of the lower portion of the shank, and tapering smoothly to the lower end thereof.

2. A spike having, in combination, a substantially round shank adapted to be turned when the spike is in use; lugs with abrupt upper surfaces and tapering lower surfaces, projecting from opposite sides of the shank; and a head comprising a substantially horizontal flange projecting at the front and one side of the shank, the other side of the head being substantially continuous with the side of the shank, and an upward non-circular projection by which the head may be turned.

GEORGE STANDFEST.
